[57] CLAIM

The ornamental design for a firearm muzzle brake, as shown and described.

DESCRIPTION

FIG. 1 is a front elevational view of a firearm muzzle brake showing my new design;

FIG. 2 is a top elevational view thereof;

FIG. 3 is a bottom elevational view thereof;

FIG. 4 is a rear elevational view thereof;

FIG. 5 is a side elevational view thereof, the opposite side being a mirror image thereof;

FIG. 6 is a front elevational view of a firearm muzzle brake showing an alternate design thereof;

FIG. 7 is a top elevational view thereof;

FIG. 8 is a bottom elevational view thereof;

FIG. 9 is a rear elevational view thereof;

FIG. 10 is a side elevational view thereof, the opposite side being a mirror image thereof;

FIG. 11 is a perspective view taken from the top and side of the firearm muzzle of my invention as shown in FIGS. 1-5;

FIG. 12 is a perspective view taken from the top and rear thereof; and,

FIG. 13 is a perspective view taken from the top and front thereof.

FIG. 2FIG. 4FIG. 3FIG. 5FIG. 1FIG. 7

FIG. 9

FIG. 8

FIG. 10

FIG. 6

FIG. 11FIG. 12FIG. 13
